INVENTOR,
Oliver E. Watson,
BY
Honora J. Smith,
ATTORNEYS.

UNITED STATES PATENT OFFICE.

OLIVER E. WATSON, OF DAYTON, OHIO.

AUTOMOBILE RADIUS ROD.

1,418,759.

Specification of Letters Patent. Patented June 6, 1922.

Application filed May 2, 1921. Serial No. 466,094.

To all whom it may concern:

Be it known that I, OLIVER E. WATSON, a citizen of the United States, residing at Dayton, in the county of Montgomery and 5 State of Ohio, have invented certain new and useful Improvements in Automobile Radius Rods, of which the following is a specification.

The principal object of my invention is to 10 provide for automobiles of the Ford type, a simple, durable and efficient radius rod structure that will successfully resist sudden jars and shocks without working loose or breaking. Other important and incidental 15 objects will be set forth in the following specification, and particularly pointed out in the subjoined claims.

In the accompanying drawings, Figure 1 is a top plan view of a part of the front 20 running gear of a Ford automobile, showing my improved radius rods secured thereto. Figure 2 is a front view of said axle, showing the front end of a radius rod secured thereto. Figure 3 is a top plan view 25 of the apex end of the radius rod structure. Figure 4 is a cross sectional view taken through the front axle, showing how one of my improved radius rods is secured thereto. And Figure 5 is a cross sectional view 30 taken on the line *a—a* of Figure 3, showing how the radius rods are welded to the forked or apex end of the radius rod structure.

Throughout the specification and drawings, similar reference characters denote cor- 35 responding parts.

Referring to the accompanying drawings, the numeral 1 designates a bifurcated mem- 40 ber having a straight rounded portion that terminates in a ball end 2 and two flat fork ends 3, 3. Each of the latter contains a longitudinal recessed portion 4 through which one end of the central flanged part 5 of a radius member 6, preferably a T-iron, projects. Each radius member 6 is 45 preferably welded to its respective fork end 3 of the bifurcated member 1, and forms therewith a strong radius rod structure. (See Figures 1, 3 and 5.)

Each radius member 6 is shaped to curve 50 downwardly from its rear portion, to bring its front end into a position beneath the axle 7 to permit one of the bolts 8 to be passed through a slot 8^a in the horizontal portion

of its front end. After this bolt is passed through said slot, a nut 9 is applied to it 55 for the purpose of drawing the horizontal portion of the radius member 6 tightly against the bottom of the axle. The middle flange portion 5 of each T-iron projects forwardly to a point where it will bear firmly 60 against the axle 7 when the horizontal portion of the T-iron is drawn tightly against the bottom of the axle by the nut. The front end of this flange portion 5, therefore, forms a shoulder which, by engaging the 65 axle, protects the bolt against shearing stresses. (See Figure 4.) Furthermore, since the outer end of the bolt passes through the slot 8^a in its respective radius member 6, it is permitted a slight longitudinal move- 70 ment to accommodate itself to longitudinal strains.

It is thus seen that I have provided a simple, strong and efficient front radius rod structure which may be readily applied to 75 an automobile of the Ford type.

I do not wish to be limited to the details of construction and arrangement herein shown and described, and any changes or modifications may be made therein within 80 the scope of the subjoined claims.

Having described my invention, I claim:

1. In a device of the type described, the combination with the axle of an automobile, of a pair of flanged radius members, fas- 85 tening elements for securing the front ends of said members to said axle, and a bifurcated apex member, provided with recesses in its fork ends to receive the flange por- 90 tions of the radius members.

2. In a device of the type described, the combination with the axle of an automobile, of a pair of radius members, a flange on each member set back a short distance from its front end to engage the side portion of 95 said axle, means for securing the front end of each member to said axle, and a bifurcated apex member, provided with longitudi- 100 nal recesses in its fork ends to receive the flange portions of the radius members.

In testimony whereof I have hereunto set my hand this 29th day of April, 1921.

OLIVER E. WATSON.

Witness:

HOWARD S. SMITH.
